PROTECTIVE HELMET OR THE LIKE

Jhoon Goo Rhee, 2525 N. Ridgeview Road,
Arlington, Va. 22207

Filed Nov. 27, 1974, Ser. No. 527,901

Term of patent 14 years

Int. Cl. D2—03

U.S. Cl. D2—232

FIG. 1 is a front elevational view of a protective helmet showing my new design;

FIG. 2 is a side elevational view thereof;

FIG. 3 is a rear elevational view;

FIG. 4 is a front elevational view thereof with the shield removed; and

FIG. 5 is a side elevational view thereof.

I claim:

The ornamental design for a protective helmet or the like, as shown.
